UNITED STATES PATENT OFFICE.

ROSS VAUGHAN, OF NEW YORK, N. Y., ASSIGNOR TO THE DISTRIBUTORS CO., OF PATERSON, NEW JERSEY.

CARTON.

968,717.

Specification of Letters Patent. Patented Aug. 30, 1910.

Application filed March 23, 1909, Serial No. 485,194. Renewed February 2, 1910. Serial No. 541,603.

To all whom it may concern:

Be it known that I, Ross VAUGHAN, a citizen of the United States, residing in New York city, county of New York, and State of New York, have invented a certain new and useful Improvement in Cartons; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to cartons for materials, such as coffee and the like, which are withdrawn in small quantities at a time, and particularly to cartons provided with pivoted means for closing their discharge openings.

The objects of the invention are to provide a carton of this nature whereby the contents may be discharged in definite quantities, which will be strong and durable, will substantially seal the contents from the deteriorating influences of the atmosphere, and which may be manufactured at an expense which will enable it to compete in point of cost of manufacture with cartons of ordinary style.

Referring to the accompanying drawings, in which the invention is fully illustrated, Figure 1 is a perspective view of the upper end of the carton with the flaps for covering its measuring device laid open; Fig. 2 is a side view of the carton, with its upper and lower portions in vertical section; Fig. 3 is another side view, taken at right angles to Fig. 2, and showing the upper portion of the carton in section, the measuring device being partly withdrawn; Fig. 4 is a detail view, showing the measuring device in vertical section and the manner in which it is hinged to the body of the carton, a certain tongue *i* being shown partway introduced into the measuring device; Fig. 5 is a perspective view of the measuring device, detached; Fig. 6 is a plan of the blank from which the carton body is formed; Fig. 7 shows the carton body formed to the point where it is ready to receive the measuring device; and, Fig. 8 is a plan of the blank from which the measuring device is formed.

For the purpose of reducing the cost of manufacture the carton as to both its body and measuring device is preferably, though not necessarily, made of heavy paper, cardboard or the like.

In Fig. 6, *a* is a blank of substantially rectangular form and adapted to be folded along the lines *b* to produce the sides *c*, *c* and *d*, *d* of a hollow rectangular shell *e* forming the body of the carton; to produce the end-walls *f* of the carton body, the blank is also folded along the lines *g* at right angles to lines *b* and formed with slits *h* coincident with lines *b* and extending to the lines *g* from the adjoining edges of the blank. The material between those two of the slits *h* which coincide with the lines of fold *b* for the intermediate narrow side or wall *c* and at what will be the upper end of the body is cut away so as to produce the tongue *i*. At each side of the last-named slits, and parallel therewith and equidistant therefrom, are formed other slits *j* extending down to the adjoining line *g*. *k*, is an elongated lip forming one vertical edge-portion of the blank.

In Fig. 8, *l* is the blank for the measuring device. The device in plan is rectangular, and its front wall in the blank is part *m*, having relatively limited vertical dimension; its side walls are the parts *n* whose upper edges *o* rise in arcs from extensions *o'* of the upper edge of part *m*, such extensions forming a stop as will appear; its back is formed by the parts *p* and *q*, which overlap each other in the ultimate form of the device; and its bottom comprises the parts *r* and *s* which also overlap each other in the final form of the device and the former of which has the extensions *t* and *u* substantially as wide as the device itself. Part *p* has an extension or lip *v* which may be slightly bent out of the plane of part *p*.

In assembling the carton body and measuring device, blank *a* is first formed into the shell *e* (Fig. 7) the lip *k* being pasted to the relatively outer or right-hand wall *c* in Fig. 6; then the flap *c'* forming the extension of the right-hand wall *c* in Fig. 6 is turned down on line *g* and flaps *d'* (forming extensions of the walls *d*) folded over flap *c'* and the one pasted on the other.

The measuring device has been meanwhile

formed from its blank as follows: It is first folded on the lines *w* into rectangular shape, part *q* overlapping part *p* and being pasted thereto, it is then folded on lines *x*, parts *t* 5 and *u* being forced up into the rectangular shell formed by the front, side and back walls of the device and part *r* being made to underlie the part *s*. As parts *t* and *u* fit snugly between the side walls *n*, *n*, parts *r* 10 and *s* are retained firmly in position as the bottom of the device. There being no paste between any of the parts except *p* and *q*, a space *y* is left between parts *u* and *p* to receive the tongue *i* of the carton body, as 15 will appear. The measuring device, thus formed, is now assembled with the shell *e*, whose flaps *c'*, *d'*, *d'* are as yet not folded down, the tongue *i* being passed into the space *y* of the measuring device and thereby 20 made to form a hinge therefor; the measuring device is now swung into the shell and flaps *c'*, *d'*, *d'* folded down. Thus assembled, the measuring device may be swung on line *g* as an axis so as either to expose 25 its interior or close opening *z*, at which time the lip *v* overlies the upper end-wall *f* of the carton, so that no crevice is exposed and the lip may be used to withdraw the measuring device; when the latter is withdrawn, 30 stops *o'* limit its outward movement so that it cannot be accidentally detached from the carton body. The carton is now filled, whereupon the flaps 2, 2, and then the flaps 3, 3, at the bottom of the carton are 35 folded down, the latter two being pasted together. Before or after this operation, the flaps 1 may be folded down and pasted to each other, and these, it will be understood, form the only part of the carton 40 which are disturbed by the user in order to have access to the measuring device and withdraw the contents.

In use, the measuring device being in its closed position, the carton is inverted to 45 such a position as to fill the measuring device; the latter is then drawn out and the quantity of contents held thereby discharged, whereupon it is returned to its normal or closing position. When the measuring device is in its open or discharging position, it effectually prevents the escape of 50 any of the remainder of the contents in the carton body.

By constructing the parts of the carton 55 in the manner herein described, it is possible to assemble them without much pasting; they may therefore be shipped in large quantities flat and quickly and readily assembled at the place of distribution.

60 In so far as the novel means herein set forth for hinging or pivotally supporting the member herein described as a measuring device is concerned, it will be understood

that I am not limited to said device performing the function of a means for measuring; 65 I claim the hinging means broadly in combination with a closure of any form. I further do not wish to be limited to details of construction herein set forth, what I claim being,

1. As an article of manufacture, a carton comprising a hollow body part having a discharge opening in one wall thereof and a measuring device pivotally arranged in the opening and having walls arranged at an 70 angle to each other and each adapted to close the opening and side walls joining the first-named walls, substantially as described.

2. As an article of manufacture, a carton comprising a hollow body part having a discharge opening in one wall thereof and a measuring device pivotally arranged in the opening and having walls arranged at an 80 angle to each other and each adapted to close the opening and side walls joining the first- 85 named walls, and also having means for limiting its pivotal movement in both directions, substantially as described.

3. As an article of manufacture, a carton comprising a hollow body part having a discharge opening in one wall thereof and a measuring device pivotally arranged in the opening and having walls arranged at an 90 angle to each other and each adapted to close the opening and side walls joining the first- 95 named walls, and also having means in its side walls engageable with the carton body to limit its pivotal movement in one direction, substantially as described.

4. As an article of manufacture, a carton 100 comprising a hollow body part having a discharge opening in one wall thereof and a measuring device pivotally arranged in the opening and having walls arranged at an angle to each other and each adapted to close 105 the opening and side walls joining the first-named walls, and also having a lip on the relatively outer one of the first-named walls engageable with the carton body to limit its pivotal movement inwardly, substantially as 110 described.

5. As an article of manufacture, a carton comprising a hollow body member having a discharge opening in one wall thereof and a measuring member arranged in the opening 115 and having walls arranged at an angle to each other and each adapted to close the opening and side walls joining the first-named walls, one of said members having a flexible tongue forming a pivotal support 120 for the measuring device, substantially as described.

6. As an article of manufacture, a carton comprising a hollow body member having a discharge opening in one wall thereof and 125 a closure member adapted to close said open-

ing, one of said members having a flexible tongue forming a pivotal support for the closure member and the other having spaced wall-portions receiving the tongue and other wall-portions closing said space at both sides of the tongue, substantially as described.

In testimony, that I claim the foregoing,

I have hereunto set my hand this 18th day of March, 1909.

ROSS VAUGHAN.
